[57] CLAIM

The ornamental design for an applicator, as shown and described.

DESCRIPTION

FIG. 1 is a front elevational view of an applicator showing my new design;

FIG. 2 is a front elevational view thereof with the cap removed;

FIG. 3 is a top plan view of FIG. 1;

FIG. 4 is a top plan view thereof with the cap removed;

FIG. 5 is a bottom view of the cap;

FIG. 6 is a perspective view of FIG. 2; and,

FIG. 7 is a perspective view of FIG. 1.

The rear and side elevational views are identical to the front elevational view; the bottom view is identical to the top view and the screw threads shown in dashed lines do not form part of the design.
